UNITED STATES PATENT OFFICE.

JAMES H. SMITH, OF PORT ARTHUR, TEXAS, ASSIGNOR OF ONE-THIRD TO JOSEPH W. BURNES, OF PORT ARTHUR, TEXAS.

SAFETY OIL-TANK.

1,060,643.

Specification of Letters Patent.

Patented May 6, 1913.

Application filed May 7, 1912. Serial No. 695,766.

To all whom it may concern:

Be it known that I, JAMES H. SMITH, a citizen of the United States, residing at Port Arthur, in the county of Jefferson and State of Texas, have invented certain new and useful Improvements in Safety Oil-Tanks, of which the following is a specification.

This invention relates to a tank for storing oil, gasoline or the like, and has particular reference to a safety tank constructed to prevent the explosion of its contents.

An important object of the present invention is to provide a tank of the above mentioned character, which is simple in construction and reliable and automatic in operation.

Other objects and advantages of this invention will be apparent during the course 20 of the following description.

In the accompanying drawings forming a part of this specification and in which like numerals are employed to designate like parts throughout the same, Figure 1 is a 25 vertical sectional view through the tank, and, Fig. 2 is a plan view of the same.

In the drawings wherein is illustrated a preferred embodiment of my invention, the numeral 1 designates a preferably cylindrical main or body portion of the tank, which may be formed of sheet metal or any other suitable material. The lower end of the body portion 1 is closed in the usual manner and its upper end is formed open, as shown. 30 The upper end of the body portion 1 is normally closed by a movable top or lid formed of an outer annular section 2 and an inner circular section 3, as shown.

Disposed within the body portion 1 is a 40 central vertically disposed post or upright 4, around which are disposed outer vertically disposed posts or uprights 5. The central circular lid-section 3 is mounted upon the central post 4, to move longitudinally thereof, the same being provided at its center with an opening through which the post passes. The outer annular lid-section 2 is provided with openings to receive the outer posts 5 and is adapted to be moved longitudinally of these posts. The posts 4 and 5 are provided with rests 6, rigidly connected therewith and the central post is provided with two of these rests, as shown. The posts 4 and 5 are provided at points above 55 and spaced from the rests 6 with stops 7,

which are rigidly connected therewith. The central post 4 has two of these stops. Mounted upon the posts 4 and 5 to move longitudinally thereof between the rests 6 and stops 7 are rings 8, as shown. The upper 60 ring 8 carried by the central post 4 has connection with rods 9, which diverge and extend upwardly for connection with the central lid section 3, as shown. The lower ring 8 carried by the post 4 and the other rings 8 65 carried by the posts 5 have connection with diverging rods 10, extending upwardly for connection with the outer annular lid-section 2. When the lid sections 2 and 3 are in their closed positions, said lid-section 2 70 engages and extends beyond the upper end of the body portion of the tank, and the lid-section 3 engages and overlaps lid-section 2. The lid-sections 2 and 3 may be moved independently of each other. 75

The posts 4 and 5 are held from lateral displacement by stay cables 11, as shown.

Connected with any part of the tank, preferably the top-section 3, is a Y-shaped structure 25, including valves 26 and 27, as shown. 80 The valve 26 is normally closed and serves to discharge gas from the tank when oil is being supplied therein. The valve 27 is also normally closed and serves to admit air into the tank when the oil is withdrawn from the 85 tank. By the operation of these two valves 26 and 27, the pressure in the tank is kept constant at all times.

In the use of the tank, the oil, gasoline or the like is stored in the body portion 1. 90 Should the contents of the tank be ignited, which is sometimes caused by the tank being struck by lightning; an explosion will take place and cause the lid-sections 2 and 3 to be elevated, whereby the flames and products of combustion are allowed to escape. These lid-sections are limited in their upward movement by the rings 8 engaging stops 7. The lid-sections 2 and 3 soon descend to their closed position, cutting off the 100 supply of oxygen to the interior of the tank and hence smothering the fire. If the tank is only partly filled, whereby the explosion is slight, the lid-section 3 only may be unseated. 105

I wish it understood that the form of my invention herewith shown and described is to be taken as a preferred example of the same, and that certain changes in the shape, size, and arrangement of parts may be re- 110

sorted to without departing from the spirit of my invention or the scope of the subjoined claims.

Having thus described my invention, I claim:—

1. The combination with a tank for holding oil or the like and having its upper end formed open, of a plurality of separate lid sections normally engaging each other and closing the open end of the tank and adapted to be elevated by different degrees of pressure within said tank, whereby only one lid section will be elevated when the pressure is slight and both lid sections elevated when the pressure is great, means to guide the lid sections during their movement, and means to limit the upward movement of the same.
2. The combination with a tank having its upper end formed open, of a vertically movable lid for normally closing the open end of the tank and formed of a plurality of inde-

pendently movable lid sections and separate means to limit the upward movement of the sections to hold them in spaced relation to each other when in the uppermost position. 25

3. The combination with a tank having its upper end formed open, of a vertically movable lid for normally closing the open end of the tank and formed of a plurality of independently vertically movable lid sections, substantially vertically disposed posts upon which the lid sections are longitudinally movably mounted, and means engaging the posts to limit the upward movement of the lid sections. 35

In testimony whereof I affix my signature in presence of two witnesses.

JAMES H. SMITH.
